(57) **CLAIM**

The ornamental design for a flexible device holding band, as
shown and described.

DESCRIPTION

FIG. 1 is a front perspective view of a first embodiment of
the flexible device-holding band showing the present design.
FIG. 2 is a rear perspective view of the first embodiment
thereof.

FIG. 3 is a side elevational view of the first embodiment
thereof, wherein the opposite side elevational view is identi-
cal;

FIG. 4 is a front perspective view of a second embodiment of
the flexible band distinguished by the addition of a vertically
opening pocket on the front surface of the flexible band,
wherein the rear perspective view of the second embodiment
remains identical to the view of FIG. 2.

FIG. 5 is an enlarged front perspective view of the vertically
opening pocket.

FIG. 6 is an enlarged rear perspective view of the vertically
opening pocket.

FIG. 7 is a lower side elevational view of the second embodi-
ment thereof; and,

FIG. 8 is an upper side elevational view of the second embodi-
ment thereof.

The broken lines shown on the drawings represent top stitching-
ing.
